Primary Examiner — Kevin K Rudzinski*Assistant Examiner* — Paul D Bohannon(74) *Attorney, Agent, or Firm* — Michael J. Foycik, Jr.(57) **CLAIM**

The ornamental design for a shirt with different colored sleeves, as shown and described.

DESCRIPTION

FIG. 1 is a front perspective view of a shirt having a left cap sleeve and no right sleeve and a right border, showing my new design;

FIG. 2 is a rear perspective view thereof;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a top elevational view thereof; and,

FIG. 8 is a bottom elevational view thereof.

In the drawings, the "+" and "—" symbols are included for the purpose of illustrating a contrast of appearance of the claimed design.

1 Claim, 2 Drawing Sheets(56)
